UNITED STATES PATENT OFFICE.

CECIL HAMELIN TAYLOR AND BOUDEWIJN B. NEUTEBOOM, OF DETROIT, MICHIGAN.

INTERNAL-COMBUSTION ENGINE.

1,151,736.

Specification of Letters Patent. Patented Aug. 31, 1915.

Application filed March 27, 1912. Serial No. 686,509.

To all whom it may concern:

Be it known that we, CECIL HAMELIN TAYLOR, a citizen of the United States, and BOUDEWIJN B. NEUTEBOOM, a subject of the Queen of the Netherlands, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

Our invention relates to internal combustion engines and an object of our improvements is to provide an improved engine and one which may be easily, neatly and cheaply constructed and assembled. We secure this object in the engine illustrated in the accompanying drawings, in which,—

Figure 1, is a vertical section of a part of a four-cylinder internal combustion engine embodying our invention. Fig. 2, is a sectional plan view, the section being taken in the plane indicated by the line 2—2 Fig. 1. Fig. 3, is a section on the broken line 4—4 Fig. 2.

30 A, is the crank case.

B B indicate the cylinders.

C, is the main shaft.

D, D is a casing closing the end of the gear casing A and provided with a bearing 35 for the shaft C.

E E is an integral head adapted to fit upon the upper ends of the cylinders B B, its lower surface being in a single plane, the upper ends of the cylinders being also in a single plane, the planed lower surface of the head E being adapted to fit against the ends of the cylinders to make a tight joint. The head E is cored out to form a water jacket F F F F F having its exit passage 40 at J.

45 G, is the intake passage for the explosive mixture. This communicates with branches g g communicating with apertures a a a a opening into the respective cylinders.

50 H, is the exhaust passage which extends in branches h h h h which branches communicate with ports or apertures d d d d opening from the respective cylinders. There are passages f f f f (Fig. 3) passing 55 above and below the passages g g and h h h h.

The head E is provided with apertures

e e opening through its lower planed surface and communicating with the water jacket in said head, the apertures e being so located and shaped as to register with apertures i i opening from the water jacket I surrounding the cylinders B B so that passages are formed from the water jacket I to the water jacket F in the head.

K, K are disk valves provided with apertures k and having vertically extending stems L L which pass through vertical apertures in the head E and are adapted to fit and rotate in vertical apertures s t. The ports k are so located that they shall register 65 with ports a and d as the valve disks K K are rotated. When a port k registers with the port a one of the cylinders is put into communication with the intake passage G and when said port registers with an aperture d a cylinder is opened to the exhaust 70 passage H.

M (Fig. 1) is a gear wheel upon the main shaft C, the teeth of which engage a gear wheel N which in turn engages a gear wheel 80 O at the lower end of a vertical shaft P, which shaft passes through an aperture or bearing p in the head E and is adapted to turn therein. The shaft P is provided with a ball bearing o at its lower end.

85 The ends of the passages G H open downward and are in the same plane as the lower surface of the head E so that the whole lower surface of the head and these passages may be faced off at one operation. The 90 apertures or bearings for the shaft P L and r are all parallel and are easily accessible so that they may be finished at one operation.

It will be observed that the cooling water will rise through the apertures i i adjacent to the exhaust passages h h h so as to keep the walls of said passages cool and is then distributed in the water jacket F of the head E and around the branches g g of the intake passage so as to supply heat for the thorough vaporization of the hydrocarbon and its thorough mixing with the air.

b, is a groove between the contiguous surfaces of the head E and cylinders B for receiving packing material, said groove extends between the passages e i and the bores of the cylinders.

What we claim is:—

1. In an internal combustion motor, the combination of a cylinder, an integral separable head for said cylinder, said cylinder and head being provided with engaging sur-

faces lying in one plane, said head being provided with a gas conduit having its outer end opening downward and terminating in the plane of the engaging surface of the head.

- 5 2. In an internal combustion motor, a cylinder having its end formed to receive a head, an integral separable head having a planed surface to fit against the end of said cylinder to form a joint, said head being provided with a passage opening to the cylinder and having the surface surrounding the passage at its outer end in the same plane as said surface of the head.
- 10 3. In an internal combustion engine, a cylinder, a separable head for said cylinder provided with intake and exhaust passages, a water jacket in said head surrounding one

of said passages, said water jacket having an opening therefrom, a cylinder having a 20 water jacket having an opening therefrom, the opening from the water jacket in said separable head being adapted to register with the opening in the water jacket of the cylinder to form a water passage, a water 25 receiving groove *b* in the joining surfaces of said cylinder and head located between the bore of said cylinder and said water passage.

In testimony whereof, we sign this specification in the presence of two witnesses.

CECIL HAMELIN TAYLOR.
BOUDEWIJN B. NEUTEBOOM.
